UNITED STATES PATENT OFFICE

OTTMAR WILHELM, OF AUGSBURG, GERMANY, ASSIGNOR TO MASCHINENFABRIK AUGSBURG-NUERNBERG, AKTIENGESELLSCHAFT, OF AUGSBURG, GERMANY, A CORPORATION OF GERMANY

TRIPPING ARRANGEMENT FOR ROTARY INTAGLIO-PRINTING MACHINES

Application filed February 16, 1928, Serial No. 254,721, and in Germany February 21, 1927.

In intaglio printing machines now used inconvenience is experienced due to the fact that upon tripping the impression cylinder from the forme cylinder the paper web is slackened. The tripping from and to the forme consequently results in alteration or loss of registration which, particularly in the case of multi-colour printing machines, impairs to a very high degree the quality of 10 the printing. Upon the machine being re-started and the printing operation being re-commenced, it may be seen that the proper registration has been disturbed.

This drawback is eliminated according to

15 the invention by the tension of the paper web being equalized upon the tripping of the impression cylinder in such a manner as to maintain approximately the same paper tension when the impression cylinder is 20 tripped to and from the forme. This compensation of the tension of the paper web may, for instance, be obtained by the adjustment, together with the impression cylinder, of a second cylinder over which the paper 25 web passes, say either the drying cylinder or the cooling cylinder, in such a manner as to maintain the paper web under tension. In this way any occurrence of register differences upon the tripping of the impression cylinder 30 from and to the forme will be entirely avoided.

The drawing shows by way of example one arrangement suitable for carrying out the invention.

35 The impression cylinder *a* and the heating cylinder *b* are both mounted in eccentric bearings *c* and *d* respectively which are connected together by rods *e* so that upon the lifting of the impression cylinder *a*, the heating cylinder will positively be moved in such 40 a manner as to maintain the tension of the paper web *f* constant.

What I claim is:

1. In intaglio printing machines, the 45 combination with the impression cylinder and means for tripping the same, of a second cylinder over which passes the paper web, and means so connecting said two cylinders that upon the tripping of said impression 50 cylinder, said second cylinder is positively

displaced so as to thereby maintain constant the tension of the paper web.

2. In intaglio printing machines, the combination with the impression cylinder and means for tripping the same, of a second cylinder over which passes the paper web, eccentric bearings for said cylinders, and connecting links between said bearings adapted to displace said second cylinder upon the tripping of said impression cylinder so as to thereby maintain constant the tension of the paper.

In testimony whereof I have affixed my signature.
